J. SCHORR

OPENING AND LOCKING DEVICE FOR CLOSURES

Filed March 23, 1922

John Schorr

INVENTOR.

UNITED STATES PATENT OFFICE.

JOHN SCHORR, OF DAVENPORT, IOWA.

OPENING AND LOCKING DEVICE FOR CLOSURES.

Application filed March 23, 1922. Serial No. 545,960.

To all whom it may concern:

Be it known that JOHN SCHORR, citizen of the United States, residing at Davenport, in the county of Scott and State of Iowa, has invented certain new and useful Improvements in Opening and Locking Devices for Closures, of which the following is a specification.

My invention relates to improvements in opening and locking devices for doors for garages, gates and similar appliances.

The objects of my invention are to provide a simple, practical, easily operated mechanism for opening and closing sliding doors, etc. and for locking them in open or closed position.

I attain these objects by the mechanism illustrated in the accompanying drawings, in which,

Fig. 1 is a plan view of my device; Fig. 2 is a detail showing the side elevation of my device, but with the rim of the wheel in section; Fig. 3 is a side elevation of the outside post carrying the sheaves or pulleys for the cable; Fig. 4 is a detail of the locking mechanism and Fig. 5 is a detail showing the means for securing the inner ends of the door levers to the operating wheel.

Similar numerals refer to similar parts throughout the several views.

My apparatus comprises a base plate, 4, which is suitably secured to the joists of a garage or building or structure by bolts, 5. A segmental rack, 32, is secured to joists of the structure by bolts or otherwise if desired. A bolt, 3, is secured in the plate, 4, and forms an axle for a wheel, 1, the hub, 2, of which is journaled on the axle, 3, and secured by a burr or nut, hubcap or other suitable device.

Levers, 16 and 17, have one end suitably secured to a fulcrum, 19, mounted upon and secured to the wheel by a clamp, 18, shown in Figure 5, by a bolt or other well known means.

In the drawings I have shown double spokes extending from the hub to the points of attachment of the clamps, 18, so as to enable the clamps to be more securely held in place, but these levers may be attached to the wheel by any of the well known means in common use for such purposes.

The opposite ends of the levers, 16 and 17, are secured to suitable brackets, 20, secured to the doors, 24 and 25, by bolts, screws or other suitable means, no claim being made

here for any particular form of bracket. The doors, 24 and 25, may be suspended upon rollers or mounted upon casters in any of the usual well known ways. I make no claim for the particular form of support for the doors.

The wheel, 1, is provided with a concave rim, 6, adapted to receive and carry an endless cable, 27. The cable is secured to the locking device shown in Figure 4 in the eye or hole, 8, formed in the rocker bar, 9. The rocker bar, 9, is fulcrumed upon a pivot, 11, secured in the head, 7, of the locking device and the head, 7, is secured to the wheel, 1, by bolts or other suitable means. Latches, 15 and 15^a, are carried in slots formed in the head, 7, and held in engagement by spiral springs, 14. Links, 12 and 12^a, having enlarged heads, 10 and 10^a, respectively, are hooked into the latches, 15 and 15^a, and pass through guide openings in the rocker bar, 9.

The cable passes from the eye, 8, of the rocker bar, 9, in each direction, partly around the wheel, 1, and passes over double pulleys or sheaves, 21 and 22, and around a single pulley, 23. The pulleys, 22 and 23, are secured to the post outside of the structure and the pulley, 21, is secured on the side or end of the structure above the doors, the cable passing out through a suitable opening in the end, 26, of the building or structure.

In Figure 1 I have shown the doors in closed position in solid lines and have shown them in open position in dotted lines.

In the operation of my device, when the doors are in the closed position as shown in Figure 1, one side of the cable on the post, 28, is pulled downward pulling the rocker bar, 9, to the left and unlocking the latch from the detent or notch, 33, allowing the wheel to revolve upon its axle and carrying the head, 7, around to the position shown in dotted lines in Figure 1. The levers will then be as shown in dotted lines in Figure 1 and the doors open. To close the doors, the operation is reversed, the other side of the cable being pulled downward, thus revolving the wheel and closing the doors. When the doors are open, the latch, 15, drops into the corresponding notch in the rack, 32, and locks the doors against movement by wind or gravity.

For garages, I prefer to mount my operating wheel in a horizontal position, but it

is obvious that it may be mounted vertically if desired.

My invention is applicable to a variety of uses and may be applied to open or close doors at a considerable distance. For use in garages, I prefer to have the operating post outside the doors, but for use in connection with warehouses, elevators, etc., the operating post may be located in the office or any other part of the building desired.

I claim:

1. In an operating device for sliding or rolling doors, the combination with an operating wheel, of a lever having one end fulcrumed to a support secured to the operating wheel and its opposite end secured to a door, and a locking head secured to the operating wheel carrying latches adapted to engage notches or seats in a rack secured adjacent the wheel.
2. In an operating device for sliding or rolling doors, the combination with an operating wheel, of levers having one end fulcrumed to supports secured to the operating wheel and their opposite ends secured to doors, and a locking head secured to the operating wheel carrying latches adapted to engage notches or seats in a rack secured adjacent the wheel.
3. In an operating device for sliding or rolling doors, the combination with an operating wheel, of a lever having one end fulcrumed to a support secured to the operating wheel and its opposite end secured to a door, a locking head secured to the operating wheel carrying latches adapted to engage notches or seats in a rack secured adjacent the wheel, a rocker bar fulcrumed in the head connected by links with the latches, and means for operating the rocker bar so as to withdraw the latches from their respective notches or seats in the rack.
4. In an operating device for sliding or rolling doors, the combination with an oper-

ating wheel, of levers having one end fulcrumed to supports secured to the operating wheel and their opposite ends secured to doors, a locking head secured to the operating wheel carrying latches adapted to engage notches or seats in a rack secured adjacent the wheel, a rocker bar fulcrumed in the head connected by links with the latches, and means for operating the rocker bar so as to withdraw the latches from their respective notches or seats in the rack.

5. In an operating device for sliding or rolling doors, the combination with an operating wheel, of a lever having one end fulcrumed to a support secured to the operating wheel and its opposite end secured to a door, a locking head secured to the operating wheel carrying latches adapted to engage notches or seats in a rack secured adjacent the wheel, a rocker bar fulcrumed in the head connected by links with the latches, and an endless cable secured to the rocker bar passing in both directions partially around the operating wheel and over pulleys secured to a post accessible to manual operation.

6. In an operating device for sliding or rolling doors, the combination with an operating wheel, of levers having one end fulcrumed to supports secured to the operating wheel and their opposite ends secured to doors, a locking head secured to the operating wheel carrying latches adapted to engage notches or seats in a rack secured adjacent the wheel, a rocker bar fulcrumed in the head connected by links with the latches, and an endless cable secured to the rocker bar passing in both directions partially around the operating wheel and over pulleys secured to a post accessible to manual operation.

In testimony whereof I affix my signature.

JOHN SCHORR.
